(57) **CLAIM**

The ornamental design for a toy tray with insert, as shown and described.

DESCRIPTION

FIG. 1 is a top plan view of a toy tray with insert showing my new design;

FIG. 2 is a bottom view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an isometric view thereof, seen from the top, front and left; and,

FIG. 8 is another isometric view thereof, seen from the bottom, right and rear.

The dash-dot-dash circles form no part of the claimed design, but serve to define the bounds of the claim adjacent to the shaded areas. The dashed lines depict the portions of the toy tray with insert that form no part of the claimed design.
